Attorney.

UNITED STATES PATENT OFFICE.

HENRY M. HANDSHY, OF HOT SPRINGS, ARKANSAS.

AWNING-REEL.

SPECIFICATION forming part of Letters Patent No. 413,935, dated October 29, 1889.

Application filed June 12, 1889. Serial No. 313,956. (No model.)

To all whom it may concern:

Be it known that I, HENRY M. HANDSHY, a citizen of the United States, residing at Hot Springs, in the county of Garland and State of Arkansas, have invented a certain new and useful Improvement in Awning-Reels, of which the following is a specification.

My invention relates to the improvement of awning-reels; and the objects of my invention are to provide a simple and inexpensive device by means of which awning-ropes may be taken up or let out to raise or lower building-awnings; to provide means whereby the awning may be held partially down, if desired; to provide simple and effectual means for connecting the ropes and the reel, and to prevent the necessity of tying the awning-ropes to prevent the descent of the awning. These objects I accomplish in the manner illustrated in the accompanying drawings, in which—

Figure 1 is a front elevation showing the ropes partially unwound therefrom. Fig. 2 is an end view of the same. Fig. 3 is a sectional view taken on line $x-x$ of Fig. 1, and Fig. 4 is a sectional view in detail of a portion of the ratchet-wheel, taken on line $y-y$ of Fig. 3.

Similar letters refer to similar parts throughout the several views.

A represents an oblong metallic plate having forwardly-projecting end flanges a . Pivotedally supported between the end flanges a is a horizontal shaft b , carrying at the center of its length a fixed notched disk or ratchet-wheel c . This ratchet is, for the purpose hereinafter specified, provided with a small perforation e in close proximity to the shaft b .

Secured to the front face of the plate A, near the lower edge and at the center of the length of the latter, is a short plate f , having projecting forwardly from its ends short arms f' . Pivoted between these arms f' is a dog or pawl g , the latter having a forwardly and downwardly extending arm from its pivot-point. The forwardly-extending arm of said pawl is held in engagement with the periphery of the ratchet c by means of a spiral spring h , made to bear between the plate f and the downwardly-extending arm of said pawl. Fixed on the shaft b , near each of its ends, is a disk i , of equal circumference with the ratchet c .

k represents a small cog-wheel fixed on the

shaft b between one of said disks i and one of the plate end flanges a . Fixed on the inner end of the horizontal arm of a crank m , 55 said arm being pivotally supported in said plate end flange above the shaft b , is a larger gear-wheel n , which meshes with the teeth of the wheel k .

p p represent the awning-ropes, of which 60 there are usually two, said ropes being wound around the shaft b —one on each side of the ratchet c —and from said shaft passing upwardly to the awning in the usual manner. The lower ends of these ropes p p are 65 secured, as shown, to and on opposite sides of the ratchet-wheel c by means of a looped wire q , made to pass through the hole e in the said ratchet, the ends of said loop tightly embracing their respective ends of the ropes p p . 70

The operation of my device is as follows: The reel-plate A having been secured to a door-frame, post, or front wall of a building near the door, the awning being raised and the ropes being coiled on the shaft b , it will be 75 seen that said ropes will be prevented from uncoiling therefrom by the engagement of the pawl g with one of the teeth of the ratchet c .

In case it is desired to lower the awning, the shaft b may be turned slightly by turning 80 the crank m , and the pawl g released from the engagement of the ratchet by pressure on the downwardly-extending arm of said pawl. The reel may then be allowed to turn by the weight of the awning to unwind the rope from the 85 reel until the awning is down. The awning may be raised by turning the crank m , which, through the gear-wheels n and k , will communicate rotary motion to the shaft b and cause the ropes p p to be taken up thereon. 90

It will be seen that the awning may be supported at any desired elevation by the engagement of the pawl g with the desired one of the teeth of the ratchet c , and that said pawl will at all times prevent the unwinding 95 of the reel in case the crank is released from the grasp of the hand.

I am aware that awning-reels have been used heretofore; but these differ from mine in points of operation and construction. 100

Having now fully described my invention, what I claim, and desire to secure by Letters Patent, is—

In an awning-reel, the combination of the
